UNITED STATES PATENT OFFICE

135,582

DESIGN FOR A HOME SHRINE OR THE LIKE

Meyer Schechter, Chicago, Ill.

Application February 23, 1943, Serial No. 109,614

Term of patent 7 years

To all whom it may concern:

Be it known that I, Meyer Schechter, a citizen of the United States, residing at Chicago, in the county of Cook and State of Illinois, have invented a new, original, and ornamental Design for a Home Shrine or the like, of which the following is a specification, reference being had to the accompanying drawing, forming part thereof.

The figure is a perspective view of a home shrine showing my design.

I claim:

The ornamental design for a home shrine or the like, as shown.

MEYER SCHECHTER.
